UNITED STATES PATENT OFFICE.

HERMAN L. GRUNDSTEIN, OF NEW YORK, N. Y.

LIFE-SAVING BOAT.

Application filed July 15, 1926. Serial No. 122,692.

This invention relates to life-saving boats. The main object of the invention is to provide a life boat which is non-collapsible and non-sinkable.

- Another object of the invention is to provide a power driving means having its source of current in the mother ship and an emergency manually operating means, should the power driving means fail.
- 10 Other objects will appear as the disclosure progresses. The drawings are intended merely to indicate a possible embodiment of the invention. It is obvious that the actual needs of manufacture may necessitate certain mechanical changes. It is therefore not intended to limit the invention to the embodiment illustrated but rather to define such limits in the appended claims.

For a more general description of the invention, attention is now called to the drawings in which a preferred embodiment is shown illustrated.

Figure 1 is a side elevation of the life-saving boat.

- 25 Fig. 2 is a rear end portion thereof.
- Fig. 3 is a section on line 3—3 of Fig 2.
- Fig. 4 is a section on line 4—4 of Fig. 3.
- Referring to the drawings in detail in which like reference characters denote like parts throughout the specification, numeral 1 designates the hull of the boat and numeral 2 partitions for dividing the interior in three water-tight compartments 3, 4 and 5. The main hatchway 6 leads to the forward compartment 3 while compartments 4 and 5 are provided with auxiliary hatchways 7 and 8. Numerals 4' and 5' designate doors in the partitions 2.

As noticed in Fig. 2 the driving mechanism is placed at the rear of the boat. Numeral 9 designates an electric motor receiving its source of current from the cable 10 connected to a generator on the mother ship (not shown). This motor is operatively connected to the propeller shaft 11 having the usual screw propeller 12 at its end and adjacent thereto is the rudder 12' guarded by a screen 11'. The propeller shaft is formed in two sections 13 and 14 with a clutch 15 in the center for engaging or disengaging the said sections. The means to slide the clutch 15 on its shaft consists of a threaded rod 16 having a fork 17 at one end engaging a groove 18 and a hand wheel 19 at the opposite end of the rod. When the hand wheel is turned clockwise or anti-

clockwise the rod will pull or push the clutch and thereby engage or disengage the section 14 of the shaft from the section 13 and thereby allow the propeller to idle or to be driven.

Integral with the clutch 15 is a bevel gear 20 which is adapted to mesh with a slidable bevel gear 21 on the motor shaft 22. To keep the gear in an upper position as shown in dotted lines a spring latch 23 is provided. The purpose of this arrangement is to disconnect the motor from the propeller shaft 11 when the manual operating means is put in operation. The mechanism to drive the propeller manually consists of a train of gears 24, 25 and 26 normally intermeshing with each other, and a pair of hand cranks 27 for revolving the driving wheel 24. The driven wheel 26 is arranged to slide on its shaft 13 so it can be in and out of mesh with the intermediate gear 25. When the manually operating means is in operation, the gear 26 will be in the position as shown in full lines in Fig. 2, and when in an inoperative position, the gear 26 will be moved to the left as shown in dotted lines. Thus the propeller shaft when under the control of the power means will not revolve the manually operating means consisting of the gears 24 and 25 and vice versa. When the manual operating means is in operation, the power means consisting of the motor 9 will not revolve.

To keep the gear 26 in its set position, a spring-operated fork 27' is provided, the ends of which engage the groove 28 to prevent any side motion of the gear. To change the position of the gear, the handle 29 is raised against the compression spring, thus disengaging the fork from the groove 28 and allowing the gear 26 to slide to the left or right.

Within the keel 30 is placed a gyroscope 31 for the purpose of steadyng the ship. This is operated by compressed air supplied from the compressed air tank 32. Intermediate the tank and gyroscope is placed a reducing valve 34. The compressed air for the tank is supplied from the mother ship through the hose 34 attached to the inlet valve 35.

To light the interior of the ship a series of electric lights 36 is provided. Current for the lights is furnished from the mother ship through the cable 10. One of the compartments is equipped with a hand-operated

magneto 37 to generate power for the lights should the supply cable 10 break. Numeral 37' designates an emergency light on top of the ship.

- 5 For keeping in communication with the mother ship, a telephone 38 is furnished. In the event of rough seas, when all the hatches are closed, the air can be purified by an air purifier 39 placed in the middle compartment. For obtaining the bearings of the vessel when partly submerged a periscope 40 is placed at the forward end. On top of the hull at the rear is placed a gong 38' operated by the usual electric actuated hammer 39' or by a hand operated hammer 40'.

Around the ship just above the normal water line is a narrow walk 41, and attached thereto is a railing 42 adapted especially for survivors of a wreck, to cling to in case of necessity. On the exterior of the hull are placed a number of life-belts 43, and adjacent thereto is a rope ladder 44, for use when needed.

20 For lifting the life-boat aboard the mother ship, three bolts 45, passing clear through the hull, having eyes 46 at the top for attachment to the mother ship's davits are provided. To the rear bolt is attached a steel cable 47 leading from the mother ship for keeping control of the life boat should it be disabled. To take up the strain of the cable 47 due to its weight, buoys of cork at frequent intervals can be attached by any suitable means thereto.

25 It will thus be seen that I have provided a life-saving boat which is safe, seaworthy and simple in operation and always in control of the mother ship. Should the electric cable break and make the motor of the life-boat inoperative, the hand-operating means can be put in operation. Excepting the magneto, there are no power-generating mechanisms, this doing away with the danger of contaminating the air when the hatches are closed and artificial air purification means is resorted to.

30 Having thus described my invention what I desire to secure by United States Letters Patent is:

35 1. In a life-boat of the class described in-

cluding a propeller, a combined power and manually operated means for driving said boat including a train of gears, one of said gears being slidable, means for making the manually operating means inoperative including a spring operated fork for latching said sliding gear out of mesh with the other of said gears so the power driving can revolve the propeller and means for making the power driving means inoperative so the manually operating means can revolve the propeller.

2. In a life-boat of the class described including a propeller shaft and propeller, a motor for driving said shaft, said shaft formed in two sections and connected by a clutch, a bevel gear integral with one portion of the clutch, another bevel gear slidably attached to the motor shaft meshing with the first mentioned bevel gear, the last mentioned gear adapted to be raised out of mesh with the first mentioned gear and kept in a raised position by a spring operated latch so the propeller shaft can be manually rotated without rotating the motor shaft.

3. In a life-boat of the class described including a propeller shaft, power means for driving said propeller, said power means consisting of a motor, a bevel gear on the motor shaft meshing with a bevel gear on the propeller shaft and a means for supplying a source of current to said motor, manually operating means for driving said propeller, said manually operating means including a driving gear supplied with a pair of hand cranks, an intermediate gear and driven gear slidably fixed on the propeller shaft, the said bevel gear on the motor shaft adapted to be kept in a raised position and out of mesh with the bevel gear on the propeller shaft so the manually operating means can drive the propeller without revolving the motor shaft, and said driven gear on said propeller shaft adapted to slide out of mesh with said intermediate gear so the power means can drive the propeller without revolving the hand operating means.

In testimony whereof I affix my signature,

HERMAN L. GRUNDSTEIN.
